FOLDING MACHINE

Leo M. Kahn, New York, N. Y., assignor to The American Laundry Machinery Company, Norwood, Ohio, a corporation of Ohio

Application May 23, 1939, Serial No. 275,158
In Great Britain May 23, 1938

18 Claims. (Cl. 270—81)

This invention relates to folding machines such as are used in laundries for folding towels, sheets and the like.

An object of the invention is to provide a simple form of machine which will enable folds to be made in articles such as towels, sheets and the like in predetermined places irrespective of the dimensions of the articles.

Another object of the invention is to provide a folding machine wherein the time of the folding is controlled by two elements, each of which is in relative motion with respect to some other element of the machine, the fold occurring upon a certain relative position of these elements, and each of which has a further relative motion with respect to those other elements, there being a second possible folding when these elements have reached another certain relative position.

Another object is to provide a machine which folds articles in two, three or four, at will, and which, being fed articles of miscellaneous sizes, folds each in a manner predetermined to be appropriate to its size and with special preliminary adjustment for each article as it is fed. Another object is to provide such a machine which may be immediately caused to change the type of folding for any, one or more, particular sizes.

Other objects of the invention will in part be obvious and will in part appear hereinafter.

The invention accordingly comprises the features of construction, combination of elements and arrangement of parts which will be exemplified in the construction hereinafter set forth and the scope of the application of which will be indicated in the claims.

For a fuller understanding of the nature and objects of the invention, reference should be had to the following detailed description, taken in connection with the accompanying drawings, in which:

Figure 1 is a diagrammatic view of a machine and its electric connections embodying one form of the invention;

Fig. 2 is an end view of a control unit the surface of a rim of which is shown in Fig. 1;

Fig. 3 is a side view, with its motor, of the unit shown in Fig. 2;

Fig. 4 is a sectional view of a portion of said unit taken along the line 4—4 of Fig. 5;

Fig. 5 is a sectional view of said unit taken along the line 5—5 of Fig. 4;

Fig. 6 is an enlarged perspective view of a portion of the outer part of said unit;

Fig. 7 is a perspective view of a part of said unit; and

Figs. 8 and 9 are diagrammatic views of modified forms of the wiring of said unit.

5 In the preferred form of the invention, the position of the fold to be made in an article is determined by, and the fold itself is made as a result of, the movement of a pair of rotary members or "riders", which movement is controlled by the passage of the article through the machine.

The bed of the machine over which the article to be folded passes comprises a pair of horizontally spaced conveyors 10 between which is 15 disposed a so-called folding finger or blade 12 provided with means for being moved at appropriate times transversely to the direction of movement of the article so as foldingly to lift the latter and present it to a pair of folding rolls 14. It is this finger which is automatically operated so as to cause the article to be folded along the desired line.

20 It will first of all be assumed that it is desired to make one central fold in each article which is fed through the machine so that the fold has to be made when the article is in such a position that half its length has been fed past the folding point. Other means will be described hereinafter for making the fold in a different position and/or for making a second fold in any article.

25 Let the distance from a particular point on the entry side of the machine (hereinafter to be referred to as the starting point) to the folding point be denoted by x and the length of the article by y . Then, any point in the article, from the time the front end of the article passes the starting point to the time when the fold is to be made, travels over a distance equal to

$$40 \quad x + \frac{y}{2}$$

If now, an arm or "rider" is set in motion at a uniform speed, when the front end of the article reaches the starting point, that rider, by 45 the time the article has reached the folding point, will have traversed a distance which can be represented by

$$x + \frac{y}{2}$$

Similarly, if a further rider is set in motion at a uniform speed, when the rear end of the article reaches the starting point, that rider, 50 by the time the article has reached the folding

point, will have traversed a distance which can be represented by

$$x - \frac{y}{2}$$

That is to say, when the article is at the folding point, the riders will be equi-distantly spaced on either side of a point distant from the common origin from which the riders move by an amount (x) representing the distance of the starting point from the folding point. What is required then is that the riders should cause the folding finger to be actuated when they take up symmetrical positions on either side of a fixed point. This can be done in a number of ways.

Blade 12 may be operated by any motive means such as a friction clutch or solenoid 16 to which is brought power from electric mains 18 and which may be in a series with a relay 20. The riders, set in motion by the article to be folded, in their turn operate the relay 20 and thereby blade 12, as will next be explained.

There is a control unit, shown as a whole in Figs. 2 and 3 and in part in Figs. 4-6, which may be placed anywhere as there need be only electric connections between it and the actual article-carrying and folding parts. It comprises two outer, stationary wheels 22 and 24 and an inner rotatable wheel 26, all coaxial. There are a plurality of riders 28 which, at certain times, are carried forward by wheel 26 and then act as electric connectors between various contacts on the rim of wheel 22 and other contacts on the rim of wheel 24. The connections thus made close appropriate electric circuits which supply energy to the folding means at appropriate times.

The riders 28, when not in operation, rest on portions of the peripheries of wheels 22 and 24, which portions are without electrical contacts. The riders in Fig. 2 are shown resting in inoperative position. Each rider has a trigger 30 pivoted thereto. The foremost rider 28f of the inoperative riders is prevented from moving forward by a release 32 which is attached to the frame of the control unit and which normally catches and holds the radially outward arm 34 of the trigger 30 of the foremost rider 28f. The second rider 28s and succeeding inoperative riders are prevented by the foremost rider from moving forward until it is their turn. The release has a tiltable lever 36 pivoted at its center. One end of the lever is in the path of arm 34 of the first rider 28f and holds the latter in inoperative position. When the release is operated, the lever tilts out of the path of arm 34 and a spring 38 attached to rider 28f pivots the trigger 30 until a trigger tooth 40 moves inward toward the rim of wheel 26 and engages with one of the teeth 42 on that rim. The motion of wheel 26 then carries rider 28f forward.

The arms 34 of successive riders are not in the same plane (perpendicular to the axis of wheel 26) but the arms 34 of alternate riders are in the same plane. Lever 36 is so positioned that, when one end thereof is raised out of the path of an arm 34 of one rider, the other end of the lever is lowered onto the path of the arm 34 of the next rider.

When rider 28f moves forward past release 36, the trigger on the second rider 28s is no longer supported by the rear of the first rider and the trigger on the second rider falls until its tooth meshes into teeth 42 on wheel 26. The latter, as it rotates, carries the second rider 28s along to the position previously occupied by the

first rider. The arm 34 of the second rider is brought against the other end of the lever 36 which raises the trigger 30 against the action of spring 38 and disengages tooth 40 from wheel 26, thereby bringing the motion of the second rider to an end at the very point where the first rider moved from. Similarly, all of the succeeding riders move forward into the position of the rider which was ahead.

After a certain time, as explained below, the release 36 releases the second rider which then proceeds to follow, at a distance, the first rider around the rim of wheel 26. The passage of these two riders completes certain electrical circuits whereby the folding apparatus is operated. Successive folding operations are each brought about by successive ones of the pairs of riders which are carried around the peripheries of wheels 22 and 24.

In Fig. 1, below the representation of the conveyors 10, folding blade 12, etc., there is shown a diagram of the contacts on the rims of wheels 22 and 24. On the wheels, of course, the contacts lie on an arc of a closed circle. In Fig. 1, the peripheries are shown as flat straight lines. One end is marked "0°" and the other is marked "360°". On the wheels, the portions marked "0°" and "360°" are immediately adjacent. The riders are shown in their inoperative position as occupying one quarter of the periphery between 0° and 90°.

The top of each fixed wheel 22 and 24 of the control unit corresponds to the marking "180°" in Fig. 1. There is a plurality of contacts, A, extending to the right of the top of wheel 24 through an arc of 90°. They lie in a plane perpendicular to the axis of wheel 24. There is another plurality of contacts, B, extending to the left from the top of wheel 24 through an arc of 90°. The latter lies in a second plane perpendicular to the axis of wheel 24. Each contact on the right is electrically connected to a contact on the left which is at the same distance from the center point marked "180°". On wheel 22 there is an electrically conducting strip 44 an end of which is in registry with the first contact on the right on wheel 24 and the other end of which is at that part of the wheel marked "360°". The strip is in a plane perpendicular to the axis of the wheel. Another strip 46 is also on the rim of wheel 22 and is in a different plane. It extends from the portion marked "90°" up to a point in registry with the last contact on wheel 24 to the left of the center point. The strip 44 is connected through switch 48 to one side of a low potential current source (transformer) 50, the other side of which is connected through switch 52 to strip 46 through the relay 20.

There is a contact button 54 on the bottom of the first rider 28f which is so positioned that, as the rider reaches the fixed contacts A, it successively contacts them. Contact button 54 is electrically connected to another contact button 56 which is positioned on the underside of rider 28f so that, as the latter moves forward, button 56 comes in contact with strip 44. There is a contact button 58 so positioned on the lower side of the second rider 28s that, as soon as the second rider enters the quadrant 90°-180°, it begins to successively contact the contacts B. Contact button 58 is electrically connected to another contact button 60 so positioned on the bottom of the second rider that when the lat-

ter is in the quadrant 90° - 180° , button 60 contacts strip 46.

One of the simplest folding operations will next be described. An article, which is for example forty inches long, is placed upon conveyors 10. Its forward edge trips a finger 62 as it passes a predetermined point. The motion of the latter causes a circuit 64 to be closed and the current in the latter operates any suitable mechanism 66 to tilt the release lever 36. Thereupon, the first rider 28f is released and begins to pass around the peripheries of the wheels 22 and 24. The motors which run the conveyors 10 and the wheel 26 may be in synchronism or the conveyors and the wheel 26 may be geared to run at the same or at predetermined relative speeds to that, when the front edge of the article is in line with the point of contact between the two folding rolls 14, the first rider is at the mid-point of the fixed wheels, shown at the top in Fig. 2 and as at 180° in Fig. 1.

Whenever the rear edge of the article passes off from the finger 62, the finger is released and breaks circuit 64, causing the operative means 66 to tilt release lever 36. With this second motion of the lever 36, the second rider 28s is set free to be carried forward by wheel 26. Contact button 58 on the second rider begins to contact the contacts B and to connect them, through contact button 60, to strip 46.

No circuit is completed, however, until the forward end of the article reaches a point as far in advance of the folding blade 12 as the rear edge of the article is behind the folding blade 12. Due to the synchronization of the conveyors and the wheel 26, the first rider will then be in contact with the contact marked "20" in group A and the second rider will be in contact with the contact marked "20" in group B. At this point, for the first time, a circuit is established, the electrical elements of which are successively the transformer 50, switch 48, strip 44, contact button 56, contact button 54, contact "20" in group A, contact "20" in group B, contact button 58, contact button 60, strip 46, switch 52, relay 20, and transformer 50. The relay 20 operates the motor or solenoid 16 and that causes folding blade 12 to rise and foldingly to lift the article up between the folding rolls 14 which catch the article and pull it as a double layer up between two pairs of spaced conveyors 68 and 70. The article now has been folded once at its mid-point. It may pass on along conveyors 70 and be removed by an operator.

Successive articles may be placed on conveyors 10, with such spacing as may be desired, and each article causes a first and second rider to be released and carried around the periphery of the fixed wheels. Each article is therefore caused by its own motion and length to be folded once along its center.

Means are provided for folding an article again after it has been folded once. Thus, there are folding rollers 114 positioned above conveyors 70 and adapted to receive and fold the once folded articles in the same fashion as rollers 14. A second folding blade 112 is positioned below the point of contact between rollers 114 and operated by a motor or solenoid 116 which is in a circuit with a relay 120.

The proper contacts and strips are provided on wheels 24 and 22 and the proper contact buttons are provided on the riders to assure the motion of the second folding blade. These contacts, etc., are as follows. There is a group of

contacts C positioned in a straight line along the periphery of wheel 24 and extending beyond a point X (see Fig. 1). The point X is at a distance from the center, " 180° ", which corresponds to the distance which the article must travel between the first and second folding blades. There is another group D of contacts on wheel 24 on the other side of that point X. Each contact in group C, which is at a predetermined distance beyond X, is connected to a contact in group D which is but one-third that distance from X. There is an electrical conducting strip 72 on wheel 22 in line with strip 46 but lying in the quadrant 180° - 270° and in registry with the contacts D on wheel 24. There is also a contact button 14 on the underside of rider 28f in line with contacts C, and there is a contact button 76 on the underside of rider 28s in line with contacts D. The buttons 14 and 56 are electrically connected, as are contact buttons 76 and 60.

The operation giving the second fold is as follows. Assume, for example, that the article originally forty inches long has been folded once and that the distance between the folding blades is thirty inches. By the time that the center of the double article is between rollers 114, the rear edge will be ten inches behind that point and it will have moved forward twenty inches from the first blade. The original forward edge of the article will have been folded back, but had it not been folded, it would have gone sixty inches beyond the zero point or first blade. The first rider reaches contact "60" in group C therefore at the same time that the second rider reaches contact "20" in group D. At that moment, the following electrical circuit is closed: transformer 50, switch 48, strip 44, contact button 56, contact button 14, contact "60" in group C, contact "20" in group D, contact button 76, contact button 60, strip 72, switch 78, relay 120 and transformer 50. The relay 120 operates motor 116 and blade 112 rises to fold the article again, this time up between folding rollers 114. It then continues between conveyors 68 and conveyors 80 until it is removed by an operator.

The second fold in the first article may be in the process of being inserted while the second article is being folded between the first pair of rollers 14. Each succeeding pair of riders have contact buttons positioned similarly to the buttons on the first pair of riders.

For clarity, only certain spaced contacts at " 10° ", " 20° ", " 30° ", etc., are shown in groups A, B, C and D, etc. In actual construction, the contacts are quite close together and would correspond to differences in length of the articles to be folded of an inch, say.

If there are no contacts A or B nearer the center, " 180° ", than those representing ten inches, then all articles which are too short to reach ten inches in front of and in back of blade 12 at the same time will go through unfolded, as there will be no activation of that blade.

Contacts on the riders and fixed wheels may be provided to give a plurality of folds. It is sometimes desirable to fold an article into three layers. Ninety inch sheets, for example, are often folded thirty inches from one end and then folded in two so as to give three layers with two folds each thirty inches from its respective end. There is shown, in Fig. 1, a group of contacts E on one side of the center point " 180° " and another group F on the other side. Each contact in one group is connected to a contact in the other which is at a distance from the center point

equal to one-half the distance of the first-mentioned contact from that point. A contact button 80 on the first of any two riders is in registry with contacts E, and contact button 84 on the second of the two riders is in registry with the contacts F. A strip 86 on wheel 22 is in registry with the contacts E, and strip 88 on wheel 24 is in registry with the contacts F on wheel 24. Contact buttons 90 on the first rider and 92 on the second rider are positioned to ride over and in contact with strips 86 and 88, respectively. By connecting the leads from the relay circuit to the strips 86 and 88 by turning switches 48 and 52, the circuits which give a fold at one-third of an article are brought into play and the circuits which were discussed above for giving a fold in the middle of an article are left open.

Assume a ninety inch article to be given a fold at one-third the distance from one end. When the forward end is thirty inches behind blade 12, the following circuit is closed: transformer 50, switch 48, strip 86, contact button 90, contact button 72, contact "60" in group E, contact "30" in group F, contact button 84, contact button 92, strip 88, switch 52, relay 20 and transformer 50. Relay 20 operates motive means 16 and blade 12 by which the sheet is folded as required.

Proper contacts on the wheels 22 and 24 are provided to cause the second fold after the first fold one-third the distance from one end of the article has been inserted. A strip 94 on wheel 24 may extend from the point X to the point 360° and there may be a single contact 96 at the point X. Contact button 98 on the first rider is adapted to contact strip 94 and contact button 100 on the second rider is adapted to contact the contact 96. Contact button 98 is connected to button 90 and contact button 100 is connected to contact button 92. Strip 97 is in registry with button 92 and may be connected to relay lead 131 by switch 78. It will be seen that, as in the foregoing cases, when the article which has had a one-third fold reaches the second folding blade, the electrical parts will be in proper condition to cause the operation of that blade whereby the article is given a second fold and has, in its final condition, three layers.

There may be an arrangement of electric connections whereby articles of lengths within a predetermined range are folded in a predetermined way and articles within other predetermined length ranges are folded in other predetermined ways. In Fig. 8 such an arrangement is shown by which articles less than ten inches long go through the machine unfolded, articles from ten to fifteen inches long are folded once in the middle, articles from fifteen to thirty-nine inches long are folded into three layers with two folds dividing the article into thirds, and articles forty inches long and longer are folded twice, giving four layers of equal length. Fixed contact groups G and H and strips 101 and 102 with co-acting rider buttons cause the folding in two of the articles from ten to fifteen inches long. Fixed contact groups J and K and strips 103 and 104 with co-acting rider buttons cause the first fold, at one-third the length, of the articles between fifteen and thirty-nine and one-half inches long. Fixed contact groups L and M and strips 105 and 106 cause the second fold in the last-mentioned articles which are thereby folded into three layers. Fixed contact groups N and P and strips 107 and 108 with co-acting rider buttons cause the first, middle fold of the two folds in the articles which are forty inches in length

and longer. Fixed contact groups Q and R and strips 109 and 110 with co-acting rider buttons cause the second fold of the two folds which together give four equal-sized layers in the articles which are forty inches and more in length. The electric leads 130, 131 and 132, shown in Fig. 8, are connected, as are the same numbered leads in Fig. 1, i. e., to transformer 50, relay 120, and relay 20, respectively.

There may be an arrangement of electric connections whereby an article of predetermined length or of length within a predetermined range may be folded in a certain way or, upon the throwing of one or more switches, be folded in another way. Such an arrangement is shown in Fig. 9, the contact groups A, B, C and D and contacts 94 and 96, all on wheel 24, being for the same purpose as the similarly lettered groups in Fig. 1. Various contacts and strips are provided on wheel 22 so that any one or more of the articles, which are from ten to thirty-nine inches long, may either be folded into four layers or into three layers. Contacts 46a, 46b, 46c, etc., are the equivalents of separate portions of strip 46 of Fig. 1, and contacts 88a, 88b, 88c and 88d, etc., are the equivalents of separate portions of strip 88 of Fig. 1. These contacts are within the ten to thirty-nine inch zone. That range may be broken down into shorter portions, if desired. Switches 52a, 52b, 52c, 52d, etc., respectively, connect lead 132 to either 46a or 88a, 46b or 88b, etc., but not to both 46a and 88a, 46b and 88b, etc. These switches may be operated separately by hand or as a unit so that when the machine is set for one type of folding, the connections for the other type of folding are automatically severed. The necessary contact buttons on the riders are provided to register with the fixed contacts and strips. Similarly, if desired, strips 72 and 97 may be broken down into separate contacts with switches so that lead line 131 may be connected to any one small portion of strip 72 or strip 97, but not both. The last-mentioned switches may be made to operate in conjunction with switches 52a, 52b, 52c, 52d, etc.

By arranging for the shifting of the full set of contacts slightly forward or backward, a setback or an overlap can be made in the folded article, if desired, to cover up so-called dog ears or bad feeding. This may be done by slightly rotating disks or wheels 22 and 24 about their axes.

Alternatively, the two riders can be made to move in different directions and cause the folding finger to be actuated when they make contact with each other. Thus, one of the riders can be made to keep in line with the front end of the article while the other can be made to move towards the folding point at the same speed but in the opposite direction from the instant at which the rear end passes a point at an arbitrary distance from the folding point, the starting point for the second rider being at the same arbitrary distance from the folding point.

Similarly, one of the riders can be made to keep in line with the rear end of the article and the other can be made to move towards it from the instant when the front end passes a point at an arbitrary distance from the folding point. The point from which the latter rider moves is at the same arbitrary distance from the folding point.

The invention can be applied to folding machines of different kinds from that assumed

above. In particular, it can be applied to so-called plate folders for small articles in which two folds are made in an article in opposite directions while the article remains at rest. In one machine of that kind in use today, an adjustable stop and plate are provided which are set in accordance with the length of the article to be folded and up to which the operator drags the article. When this stop is reached, the article is gripped to determine the line of the first fold and a pivoted plate or flap is swung to make the fold. The other end of the article is then folded over the free end of the folding plate. As the same plate is used for articles of different sizes, the folded portions are frequently of different lengths. In applying the invention to that kind of machine, the above-mentioned adjustable stop may be dispensed with. The operator drags the article over the bed of the machine. The bed comprises friction gearing which is rotated by the dry article or by the operator when placing the article which causes a rider situated beneath the article to be moved backwards. This rider carries a photo-electric cell which remains inoperative when obscured by the article, or mechanical power means can be used to set the rider in motion by the article reaching the folding point. When the cell reaches the end of the article, it is illuminated and causes a gripper to grip the article and arrest its movement. If the friction gearing has a two-to-one ratio so that the rider moves back twice as fast as the article moves forward, and the gripper is situated at the point from which the rider started, the article, when arrested, will overlap the gripping point by one-third of its length. If, now, a folding plate comes into action, the leading third of the article will be folded back. The trailing end can then be folded over the leading end. Provision can be made in a simple manner for the three portions of the folded article to be of equal length. It is only necessary that the movement of the rider should be accompanied by a proportional movement of the folding plate so as to adjust the effective length and movement of the latter past the gripping point. This overcomes the disadvantage of the machine referred to above in an inexpensive manner, and because when folding narrow articles it may not be essential to effect the folding at predetermined points by remote control.

A pulley on the shaft of the motor which rotates wheel 26 may be connected by a belt to a pulley on a shaft of the conveyor system, thus synchronizing the control unit and the article conveyors.

In the above-described machines, two riders control the first fold in an article and the same two riders control the second fold in that article. The same result, as far as the second fold is concerned, may be obtained less simply by using the first rider and a third rider which starts when the first fold is made, in which case the machine operates as though the once folded article were a flat unfolded article and a new mid-point, 180°, is used for the second operation. Consider a once-folded article as a new article of shorter length. Then the second fold is in the middle of the new article whether that article was previously folded in half or at a one-third distance. The contacts, for the second fold, for the first and third riders would be spaced in pairs, one in each pair being connected to the other new mid-point. By spacing the points as at C and

D in Fig. 1, the necessity for the third rider is obviated.

Since certain changes may be made in the above construction and different embodiments of the invention could be made without departing from the scope thereof, it is intended that all matter contained in the above description or shown in the accompanying drawings shall be interpreted as illustrative and not in a limiting sense.

It is also to be understood that the following claims are intended to cover all the generic and specific features of the invention herein described and all statements of the scope of the invention which, as a matter of language, might be said to fall therebetween.

Having described my invention, what I claim as new and desire to secure by Letters Patent is:

1. In a device for folding articles, the combination comprising a plurality of movable elements, means for spacing said elements at a distance which is a function of the length of an article to be folded, means for moving said elements, while so spaced, to some predetermined position, and folding means set in operation by said elements in said position and adapted for folding said article.

2. In a device for folding articles, the combination comprising a plurality of movable elements, means for automatically spacing said elements at a distance which is a function of the length of an article to be folded, means for moving said elements, while so spaced, to some position, and folding means set in operation by said elements in said position and adapted for folding said article.

3. In a device for folding articles, the combination comprising a plurality of movable elements, means for spacing said elements at a distance which is a function of the length of an article to be folded, means for moving said elements, while so spaced, to some position, folding means set in operation by said elements in said position and adapted for folding said article, means for moving said spaced elements to another position, and folding means set in operation by said elements in said other position and adapted for folding said article again.

4. In a device for folding articles, the combination comprising a plurality of movable elements, means for spacing said elements at a distance which is a function of the length of an article to be folded, means for moving said elements, while so spaced, to some position, folding means set in operation by said elements in said position and adapted for folding said article, means for moving said spaced elements, while still so spaced, to another position, and folding means set in operation by said elements in said other position and adapted for folding said article again.

5. In a device for folding articles, the combination comprising a plurality of movable elements, means for spacing said elements at a distance which is a function of the length of an article to be folded, said means being operated by the passage of the front and the rear of such an article, means for moving said elements, while so spaced, to some position, folding means set in operation by said elements in said position and adapted for folding said article, means for moving said spaced elements to another position, and folding means set in operation by said elements in said other position and adapted for folding said article again.

6. In a device for folding articles, the combination comprising a plurality of movable elements, means for spacing said elements at a distance which is a function of the length of an article to be folded, means for moving said elements while they are spaced at said distance, means for folding said article, other elements, means for changing the distance between the first-mentioned elements and said other elements, and operative means for said folding means and put in operation when said elements have a predetermined spatial relationship.

7. In a device for folding articles, the combination comprising a plurality of movable electric contacts, means for spacing said contacts at a distance which is a function of the length of an article to be folded, means for causing said contacts, so spaced, to move to become part of an electric circuit whereby said circuit is closed, and means operated by power associated with said circuit and adapted for folding said article.

8. In a device for folding articles, the combination comprising a plurality of movable electric contacts, means for spacing said contacts at a distance which is a function of the length of an article to be folded, means for causing said contacts to become part of an electric circuit whereby said circuit is closed, means operated by power associated with said circuit and adapted for folding said article, means for causing said contacts to become part of another electric circuit whereby said other circuit is closed, and means operated by power associated with said other circuit and adapted for folding said article.

9. In a device for folding articles, the combination comprising a plurality of movable electric contacts, means for spacing said contacts at a distance which is a function of the length of an article to be folded, means for causing said contacts to become part of an electric circuit whereby said circuit is closed, means operated by power associated with said circuit and adapted for folding said article, means for later causing said contacts to become part of another electric circuit whereby said other circuit is closed, and means operated by power associated with said other circuit and adapted for folding said article again.

10. In a device for folding articles, the combination comprising means for successively moving a plurality of articles which are of different lengths and which are to be folded, a multiplicity of movable electric contacts, means for spacing one plurality of said contacts at a distance which is a function of the length of one of said articles to be folded, means for causing said contacts to become part of an electric circuit whereby said circuit is closed, means operated by power associated with said circuit and adapted for folding said one article, means for spacing a second plurality of said movable electric contacts at a distance which is a function of the length of another of said articles, said other article being moved after said one article and being of a length different from said one article, means for causing said second plurality of contacts to become part of an electric circuit whereby said circuit is closed, and means operated by power associated with said circuit and adapted for folding said second article.

11. In a device for folding articles, the combination comprising means for folding a predetermined type of fold into articles having lengths within a predetermined range, means for folding another type of fold into articles having lengths

within a different range, said first and second named means including electric circuit portions independent of each other, electric-circuit-completing, rider means controlled by the length of any article about to be folded and adapted for operating whichever of said folding means is for folding an article of such length, means for rendering the second-mentioned means inoperative, and means for causing the first-mentioned means to fold all of said articles.

12. In a device for folding articles, the combination comprising a plurality of movable elements, means for moving said elements at the same speed, operated by an article which is to be folded, and means for folding the article and set in operation by said elements after they have been set in motion, said last named means including an electrical circuit completed through a plurality of said movable elements simultaneously.

13. In a device for folding articles, the combination comprising means providing a path, a plurality of elements movable along said path, means for successively stopping said elements at an initial point of said path, means for releasing one of said elements from said initial point of said path, whereby said one element moves along said path, and for arresting a second element at said point, means for moving said elements, the last-mentioned means being operated by an article which is to be folded, and means for folding the article and set in operation by said elements after they have been set in motion along said path, said last named means including an electrical circuit completed through a plurality of said movable elements simultaneously.

14. In a device for folding articles, the combination comprising fixed means having a plurality of electric contacts positioned in a circle thereon, certain ones of said contacts each being connected only to a respective certain other one of said contacts, a plurality of elements movable with respect to said contacts and having contacts positioned so that certain of the fixed and movable contacts touch each other as said elements move, means for moving said elements, said means being operated by an article which is to be folded, and means for folding the article and set in operation by power directed by circuits established by the touching of said movable contacts with those of said fixed contacts which are connected to each other.

15. In a device for folding articles, the combination comprising fixed means having a plurality of electric contacts positioned in a circle thereon, certain ones of said contacts each being connected only to a respective certain other one of said contacts, a plurality of elements movable with respect to said contacts and having contacts positioned so that certain of the fixed and movable contacts touch each other as said elements move, means for moving said elements, said means being operated by an article which is to be folded, and means for folding the article and set in operation by power directed by circuits established by the touching of said movable contacts with those of said fixed contacts which are connected to each other, said connected ones being connected in pairs, one of the contacts of one of said pairs being on one side of a predetermined point on said circle and the other contact on the other side, the other pairs also bracketing said point.

16. In a device for folding articles, the combination comprising fixed means having a plural-

ity of electric contacts positioned in a circle thereon, certain ones of said contacts each being connected only to a respective certain other one of said contacts, a plurality of elements movable with respect to said contacts and having contacts positioned so that certain of the fixed and movable contacts touch each other as said elements move, means for moving said elements, said means being operated by an article which is to be folded, and means for folding the article and set in operation by power directed by circuits established by the touching of said movable contacts with those of said fixed contacts which are connected to each other, said connected ones being connected in pairs, one of the contacts of one of said pairs being on one side of a predetermined point on said circle and the other contact being at the same distance from said point.

17. In a device for folding articles, the combination comprising a movable element, means for starting said element into motion when the article to be folded reaches a predetermined point, a second movable element, means for starting said second element into motion when the ar-

ticle to be folded passes said predetermined point, and means for folding the article and operable by said elements when said elements are simultaneously in predetermined, respective positions, said last named means including an electrical circuit completed through a plurality of said movable elements simultaneously.

18. In a device for folding articles, the combination comprising a movable element, means for starting said element into motion when the article to be folded reaches a predetermined point, a second movable element, means for starting said second element into motion when the article to be folded passes said predetermined point, and means for folding the article and operable by said elements when said elements are simultaneously in predetermined, respective positions, said means for moving being adapted for moving said elements at the same speed whereby said elements, when in motion along the same path, are maintained at a constant distance apart.
